GLASSWARE FORMING MACHINE

Frank O'Neill, Toledo, Ohio, assignor, by mesne assignments, to Owens-Illinois Glass Company, Toledo, Ohio, a corporation of Ohio

Application December 26, 1930, Serial No. 504,844

4 Claims. (Cl. 49—5)

This invention relates to the handling of molten metal in the forming of such into ware.

This invention has utility in the suction gathering, forming of glass blanks therefrom and blowing such into finished ware, especially in connection with two table types of machines as continuously rotatable.

Referring to the drawings:

Fig. 1 is a fragmentary plan view of an embodiment of the invention, the blank table in gather position at a tank being shown;

Fig. 2 is a section on the line II—II, Fig. 1;

Fig. 3 is a fragmentary plan view of the blow table in completing the machine of Fig. 1;

Fig. 4 is a plan view of the machine truck or platform with features of table drive and control;

Fig. 5 is a plan view of blank table or carrier control cams of the region below the carrier;

Fig. 6 is a section on the line VI—VI, Fig. 5;

Fig. 7 is a section on the line VII—VII, Fig. 5;

Fig. 8 is a section on the line VIII—VIII, Fig. 1;

Fig. 9 is a section on the line IX—IX, Fig. 8;

Fig. 10 is a view in vertical section of the burner for treating the blank lower portion just in advance of transfer;

Fig. 11 is a section on the line XI—XI, Fig. 10;

Fig. 12 is a section on the line XII—XII, Fig. 8;

Fig. 13 is a plan view of the blank mold bottom closure or baffle of two-bladed shear form;

Fig. 13^a is a section on the line XIII^a—XIII^a,

Fig. 13;

Fig. 14 is a section on the line XIV—XIV,

Fig. 13;

Fig. 15 is a view of portions of the nipple box at gather position;

Fig. 16 is a plan view of portions of a blank arm and its carrier;

Fig. 17 is a section on the line XVII—XVII,

Fig. 16;

Fig. 18 is a section on the line XVIII—XVIII,

Fig. 16;

Fig. 19 is a section on the line XIX—XIX,

Fig. 16;

Fig. 20 is a view from the line XX—XX, Fig. 1, looking into the cam controlling the neck-finish opening in the region of transfer;

Fig. 21 is a plan view of portions of the machine at the transfer region;

Fig. 22 is a section on the line XXII—XXII,

Fig. 21;

Fig. 23 is a fragmentary view of an adjustable control link for blank mold section operation;

Fig. 24 is a plan view of the ported collar on the

blow carrier column, upon which collar the ported timing devices of the valve are mounted;

Fig. 25 is a plan view of control cams for the blow or second carrier as about the column below the carrier;

Fig. 26 is a plan view of the valve devices mounted above the collar of Fig. 24;

Fig. 27 is a section on the line XXVII—XXVII, Fig. 26;

Fig. 28 is a section on the line XXVIII—XXVIII, Fig. 26;

Fig. 29 is a section on the line XXIX—XXIX, Fig. 28;

Fig. 30 is a section on the line XXX—XXX, Fig. 28;

Fig. 31 is a section on the line XXXI—XXXI, Fig. 3;

Fig. 32 is a view of features of the blow mold bottom in up position, as distinguishing from the drop or down position thereof in Fig. 31;

Fig. 33 is a section on the line XXXIII—XXXIII, Fig. 31; and

Fig. 34 is a view of blank mold interior spray device and the control therefor.

The machine is shown as a readily portable installation. It has main platform 1 mounted on rollers 2. Columns 3, 4, rise from the platform 1.

The drive and control

Electric power line conduit 5 extends to switch 6 on the platform 1. Throwing in this switch 6 effects starting of electric motor 7 having shaft 8 carrying pulley 9 from which extends belt 10 about pulley 11 on shaft 12 mounted in bearings 13, 14, rising from the platform 1 on which the motor 7 is also mounted. On this shaft 12 is nut 15, adjustable to vary the compression of helical spring 16 for holding splined clutch collar 17 into transmission engagement with clutch member 18 on shaft 19 aligned with the shaft 12 and mounted in bearings 20, 21, rising from the platform 1. This shaft 19 has thereon worm 22 in mesh with worm wheel 23 loose on shaft 24 rising from the platform 1. Housing 25 is about this worm wheel 23 and gear 26 is fixed with the gear 23. This gear 26 is in mesh with gear 27 on the column 3 determining the driving rotation of the blank mold carrier. This first carrier gear 27 is directly in mesh with gear 28 on the column 4 as the drive for the blow table or second carrier in synchronism with the first carrier. In practice hereunder, it is contemplated the rotation shall be continuous.

For bringing the carriers to a desired angular

60

105

110

position, manually, it is only necessary to operate hand wheel 29.

Opening of valve 30 permits supply of power air to line 31. Emergency valves 32 at various positions about the machine may be thrown to cut in air to power cylinder 33, thereby through lever 34 shifting clutch collar 17 away from its companion clutch member 18 against the spring 16. The motor 7 is thus rendered ineffective for driving the worm 22. Resetting of the thrown emergency valve 32 to running position effects exhausting of the cylinder 33 through such valve allowing the spring 16 to force the collar 17 into engagement with the clutch member or collar 18 and the machine to again enter upon regular running operation.

In tank 35 is molten glass supply or pool 36. From this tank 35 there protrudes laterally, overhang 37 having exposed area 38 into which molten glass 39 may flow up to the level of the pool 36, by way of opening 40 under arch 41 (Fig. 2). Approximating the underside of the arch 41 above the level of the pool 36, there is refractory metal shield 42 resting on the overhang and extending to the arch 41, with an opening 43 in such shield which restricts the area exposed, reducing the atmospheric cooling of the molten glass in the pool 36. Herein this opening 43 is shown of arc form for suction gather of molten glass upward through open bottom 44 into blank mold 45, 46, during the continued movement of the blank mold.

The blank mold carrier

35 The blank carrier gear 27 (Fig. 8) is fixed with spider 47 upwardly therefrom about the column 3 and sustained by anti-friction bearing 48. The spider 47 has fulcrum bearings 49 for outwardly extending rocker arms 50. Vertical pin 51 in the 40 arm 50 mounts the blank mold sections 45, 46, to swing toward and from each other. Additional pin 52 further outward on the arm 50, pivotally mounts neck finish or minor mold sections 53, 54, for aligned closing over the closed major mold sections 45, 46. Depression of wedge 55 (Fig. 8) against the resistance of spring 56 by pressure applied on plunger head 57 effects thrusting of the neck finish mold sections 53, 54 apart or into open position against the resistance of tension 50 helical spring 58 (Fig. 21) therebetween.

The nipple box

The arm 50 forwardly of the minor mold section opening plunger head 57 has housing 59 (Figs. 8, 15, 19). Ears 60 from said housing 59 have bearings 60' which mount upwardly extending lever 61 terminating in roller 62 at its free end. This lever 61 mounts pin 63 which has pivot pin connection 64 with link 65 having slots 66 with which coats pin 63' carried by the ears 60. This link 65 has link 67 therefrom to piston 68 reciprocable in the housing 59 by rocking of the lever 61.

At the position of the parts in Fig. 8, suction in chamber 69 of the arm 50 is in communication by ducts 69' with chamber 70 from which extend ducts 71 through member 72. These ducts 71 extend into the blank mold sections for there developing the suction gather. At the position in Fig. 19, the suction gather has occurred. Lifting of the piston 68 has raised plunger 73 and carried sleeve 74 upward therewith for connecting pressure air supply chamber 75, by way of ports 76, 77, 78, with chamber 79 about the plunger 73 for entrance of blank blowing pressure air

through neck 80 into blank body 81. The sleeve 74 acts as a valve to prevent blowing air to pass through the ducts 71 in the member 72.

Upon completion of the blank blowing operation, and before transfer or removal of the formed blank from the blank mold, the lever 61 is further rocked to pull upward the member 72 against the resistance of spring 82. This operation pulls upward neck finish mold ring 83 clear of neck bead 80 of the blank, as in the initial upward action transmitted from the lever 61. Yieldable seating of the plunger 73 in the ring 83 is due to action of spring 84. The inclusion of this neck ring mold section 83 is of more value for adoption in connection with so-called wide-mouth ware and milk bottles to form ledges and aiding to prevent blowing away of such ledges and for an additional chilling for a predetermined section of the neck or finish.

The further adjustable rocking of the lever 61 after lifting the ring 83, may depress the wedge 55 for opening the neck finish mold sections 53, 54, in finally releasing the blank or parison in effecting a transfer.

The gather

Fixed with the arm 50 as an angle lever is depending arm 85 carrying fixed therewith shaft 85' terminating in roller 86 having assembly means 87 for eccentric sleeve 88 locked in its angular position as to the arm 85 by set screw 89 (Fig. 8). For holding the blank mold sections as closed to have their open bottom 44 approximate a horizontal plane, the roller 86 rides along fixed cam 90 (Fig. 5). This cam 90 is mounted on the column 3.

In the rotation of the carrier 27, 47, the roller 86 rides from the concentric cam 90 to cam 91 outward to lift holding cam portion 92, effective to tilt the arm 50 to such extent that the blank mold sections 45, 46, are clear of the shield 42 at the overhang 47. Further travel of the roller 86 into dip portion of cam 93, lowers the open bottom 44 into the opening 43 of the shield 42 to approximate the upper surface 39 of the molten glass.

Air suction line 94 (Figs. 16, 17, 18) has connection 95 with block 96. Nicety in angular adjustment may be had to vary application of vacuum to charge the blank in a restricted exposed area of the pool 36. This adjustment is effected by shifting the block 96, which is brought about by rotation of threaded stems 97, 98. This block 96 rests on plate 99 having ports 100 therein for the respective blank mold carrying rockers 50, 85. Each port 100 is in communication with a chamber 101 having therein check valve 102 (Fig. 8) operable by reduced pressure in such chamber 101. Housing 103 for this chamber 101, has a rigid tubular extension 104 of arc or gooseneck form extending through gland 105 for communication with the chamber 69. The arc of this duct or pipe 104 is on a radius from the fulcrum bearing 49. It is thus seen that angle lever 50, 85, may rock relatively to the spider 47 and that there is still preserved air connection therebetween at the gland 105 through which the pipe 104 may reciprocate, while the air connection to the rotary chamber 101 is from the block 98 having timed communication through a port 100. For a brief angular travel the suction is thus effective, timed to occur at the touching or approximate touching of the glass surface 39 by the open bottom 44 of the blank mold.

The roller 86 rides out of this dip portion 93

150

upon cam portions 105, 106, back to concentric portion 90, in lifting the blank from its horizontal bottom gathering position for tilting over the forebay and then settling back to its normal travel 5 region to approximate perpendicular or vertical position for the closed blank mold.

The shear

10 Loose upon the depending arm 85 is sleeve 107 (Fig. 8) from which rises fulcrum bearing providing bracket 108. From this fulcrum bearing arm 109 extends upwardly and outwardly. Set screws 110 (Figs. 13, 14) may be slackened as to one there- 15 of and run up as to the other to effect desired tilting of flat stem 111 terminally carrying plate 112 to have such plate a desired rake or angle for approach to the opening 44 of the blank mold. This plate 112 is provided with V-shaped notches 113 to serve as severing means or a shear, and is 20 reversible for different assembly so that one notch may be used after the other has become worn to an undesirable extent. This plate 112 is provided with notches 112', one of which seats at fixed pin 111' where it is held by opposing gib 25 112'' at the beveled longitudinal side of the plate 112. Screws 111'' anchor the gib detachably to permit the reversal of the plate 112.

This shear arm 109 as carrying the blank mold combined shear and baffle plate or bottom closure, 30 is not directly mounted on the fulcrum bearing bracket 108, but has dove-tail seat 114 as a slide connection with depending arm 115 which has direct mounting on pivot bearing 116 in the bracket 108 (Fig. 8). This depending arm 115 terminates in roller 117. This arm in the region of the slide is provided with ear 118 for screw 119 extending to ear 120 fixed with the arm 109, thereby adjusting nicely the horizontal plane for the plate 112 up and down as to the 35 arm 115. Clamp 120' locks arm 109 in adjusted position.

The shaft 85' has fixed therewith cam 121, 122 (Fig. 12), with which the roller 117 may coact. The portion 121 serves to hold the baffle 112 in closure position. From the sleeve 107 there extends bracket 123 downward past the roller 86 to arm 124 pivoted on the shaft 85' and carrying roller 125 which as riding on concentric cam 126 has effected such angular shifting of the sleeve 107 that the baffle or closure plate 112 is away from the blank mold bottom opening 44.

In the closed circuit cycle of travel of the blank mold, the roller 125, rides along the cam 126 (Fig. 5) and cam portions 127, 128 into cam 129 for swinging the closure 112 under the blank mold as such rises from the glass pool with a gather sucked thereinto. This shearing operation is effected at the cam portion 130 with cam 131 therefrom holding the plate 112 as a closure during blank blowing.

The blank blowing may continue along cam portion 132, while cam 133 (Figs. 5, 6) mounted in guide 134, may be angularly shifted by handle 135 and locked by set screw 136, in thereby adjusting the time for swinging of the closure 112 away from the bottom 44 of the gather in the blank mold.

Gather cut out

70 Rotary stem 137 (Figs. 5, 7) operable on threaded stem 138 may shift block 139 to cause the cam 93 to rock on its bearings 140 in bringing arc face 141 outward more or less to approximate the range of cam portions 92, 105. 75 There is thus provided cam continuity for vary-

ing or eliminating all dip at the gather region. The manual adjustments have utility for regulating the dip descent to the height of the glass in the pool or for other control purposes in machine operation, effective during the running of the machine.

As a safety device against stopping the machine with a blank mold in the pool, when an emergency stop is made, line 142 extends to cylinder 143 (Figs. 4, 7) for moving the cam face 141 outward into dip eliminating position by the action of piston rod 144, where it is held by the power air until the emergency condition is removed. Upon starting of the machine, the load of the roller 86 will reset the cam 93 as then permitted by the cylinder 143 which has been exhausted. The power air supply line 31 has branch to valve 31' opened when there is such resistance to machine driving that the clutch pins of the clutch member 18 thrust the collar 17 by sliding past the sockets therein. This automatic unclutching, not only stops the carrier rotations for the machine, but swings the arm 34 to open the valve 31'. Power air is thus supplied to line 32' independently of by way of the valve 32. The cylinder 33 thus acts to hold the machine drive disconnected. This power air also flows past check valve 32'' and by way of the line 142 to rock the cam face 141 into position to hold the gather mold sections 45, 46, clear of contacting the pool of 105 glass.

Blank blowing

Cam 145 coacts with the roller 62 after the transfer for rocking the lever 61 outward or upward for bringing the plunger 73 into fully depressed position, which position it retains until past the gather station, when the roller 62 rides into cam 146 (Fig. 1) for lifting the plunger 73 in bringing the nipple box elements into the position in Fig. 8. Adjusting device 147 is provided for effecting angular shifting of this cam 146 for timing the initial opening former or plunger 73 for regulating the chilling of the neck and lip.

Pressure air lines 148 extend to valves 149 in block 150 (Fig. 16) riding on the ring plate 99. The valves 149 determine the effective arc for blowing of air through the port 99 into the chamber 101 from which flexible ducts 151 (Fig. 8) extend to the chamber 70.

During the blowing operation for the blank, the plunger 73 is maintained withdrawn from the blank 81. Cam elements 152 are assembled for the desired arc interval, and removed as it is desired to shorten such interval, with placing of cam portion 153 terminally (Fig. 1). Upon passing the cam portion 153, the roller 62 is operated to such extent that the ring 83 is lifted clear of the blank lip 80.

Blank mold opening

From the blank mold sections 45, 46 (Fig. 16), extend adjustable links 154 to arms 155 of angle levers having fulcrum bearing pins 156. Fixed with the arm 155 is arm 157 having yieldable link 158 extending to arm 159 having fulcrum bearing 160. Fixed with the arm 159 is arm 161 having roller 162 (Fig. 8). This roller 162 as riding into cam portions 163, 164 (Fig. 1), effects opening of the blank mold by moving the sections 45, 46, away from each other, thereby leaving the blank suspended from the neck finish mold sections 53, 54.

This opening of the major blank mold sections has released the neck finish mold sections, for 150

adjustable compression linkage devices 166 (Figs. 16, 23) have rocked angle levers 167 to have adjustable stops 168 clear of the sections 53, 54.

Blank heating

There is utility for superior ware forming, and even for removing shear mark in the formed blank, by exposing such as suspended to a reheating operation. To this end valve 169 in gas line 170 extends to fitting 170'. Air line valve 171 in air line 172 controls air supply to this fitting which extends upwardly to flare burner device 173 (Figs. 10, 11) at box 174 having upper notch way 175 thereacross as a passage for the lower portion or body 81 of the suspended blank. This burner device may be accurately controlled for this heating blast to melt out any shear mark or deformation at the closure region.

Transfer

The suspended blank 81 as passing the burner 173, is held only by the major or neck finish blank mold sections 53, 54. The roller 62 as approaching the region of meshing between the gears 27, 28 of the respective carriers, rides into cam portion 176 (Figs. 1, 20) which effects sufficient depressing of the wedge 55 (Fig. 8) to provide a looseness to establish a minute movement apart of the sections 53, 54. Riding from this cam portion 176 into cam portion 177 then effects definite opening, but not sufficient to drop the suspended blank. At cam section 176 the blank neck 80 is freed to wobble in seeking its center in blow mold sections 178, 179 (Fig. 3) as closing thereabout, but is sufficiently sustained not to be dropped thereinto until the roller 62 rides upon cam portion 177. These movements in the continuous rotation of the carriers are so timed that the blow mold 178, 179, is substantially closed for sustaining the blank neck 80 at the full release operation of the cam 177.

The region of transfer is desirably in the vicinity of the meshing of the gears 27, 28, or about at center line 181 between the columns 3, 4. The speed of operation and character of ware makes desirable flexibility in operation for locating the point for loosening the blank by the cam 176 and full release by the cam 177 to match the seams or mold marks. This is effected, even during the operation of the machine. Fixed with the cam 176 are ears 182 in which is slidable stem 183 having threaded portion 184. This stem 183 is rotatable in guide ear 185 fixed with the relatively slidable cam unit 177. Collars 186 at the ear 185 are fixed with the stem 183 and transmit longitudinal shifting of the stem 183 for positive relocation of the cam 177, as to the line 181, for such advanced or retarded performance as may be in keeping with efficient practice in the machine operation.

Upon passing the transfer station, fixed cam 180 is effective for wide-spread opening of the mold sections 53, 54, permitting more freedom in heat radiation at the high speed of machine performance hereunder.

Spray

Besides the full opening of the neck finish sections 53, 54, and the wide opening of the sections 45, 46, for mesh clearance with the closing and closed blow mold sections 178, 179, at the region of the line 181, further mold care provision may be had by directing a spray thereinto. When the liquid be oil, it may serve supplementally as a lubricant, especially for elements of the nipple box.

Reservoir 187 (Fig. 34) is provided with valve 188 which may be adjusted for a slow dripping action into duct 189. Pressure air line 190 is shown as having valve 191 which may be struck by a moving part of the machine, as pipe 104, to give but a timed snap opening of the valve 191 for a gust of air to blow into the pipe 189 (Figs. 1, 34) for vaporizing a jet of the cooling medium upwardly discharged by jet 192 into the open blank mold sections and upwardly therepast into the nipple box thereover.

The blow mold carrier

The gear 28 is mounted concentrically of the column 4 and sustained by antifriction bearing 193 (Figs. 21, 31). Fixed with the gear 28 and thereabove about the column 4 is spider or table section 194 having an annular series of blow molds thereon for, in sequence, coming to transfer proximity with the annular series of blank molds of the blank carrier 27, 47. Axially parallel with the column 4, the spider 194 has hinge pins 195 for the pairs of blow mold sections 178, 179, having open bottom 196.

Blow mold bottom

The spider 194, below the pin 195 has horizontal pin 197 pivotally mounting depending arm 198 (Figs. 31, 32) having offset therefrom socket 199 with which coacts compression spring 200 for yieldingly thrusting blow mold bottom 201 upwardly. The arm 198 is operated by yieldable link 202 extending to lever 203 having fulcrum bearing 204 on the web of the gear 28 adjacent opening 205 therein through which this lever 203 extends to have its roller 206 ride on fixed cam 207.

Hinge pin 208 at the connection of the link 202 with the arm 198, pivotally mounts auxiliary arm 209 having terminal nose 210. The cam 207 in the approach to the line 181 has acted upon the roller 206 to swing yieldingly the socket 199 upward into position for the blow mold sections to close thereabout. Cam 211 is then acting upon roller 212. Just after the transfer station, and desirably before any blowing has occurred, cam 213 (Fig. 25) acts upon the roller 212 to move slide 214 (Fig. 31) outwardly. Adjustable clearance 215 therein permits engagement of the nose 210 (Fig. 32) so that a final thrust is effective on the arm 209 transmitted by slot connection 216 and stem 217 to lock the bottom 201 in elevated position for positive resistance to blowing of the blank to finished ware form in the blow mold 178, 179. This movement of the mold bottom 201 upward to the position shown in Fig. 32, thrusts such bottom 201 up into contact with the warmer run-out portion of the blank bottom, tending to flatten such bottom out around the sheared edge.

This has a reheating influence on such chilled edge and tends to spread out such shear mark. Upon blowing of the blank to ware form, such shear mark is dissipated into a larger diameter region, and there is promoted the tendency to have such mark disappear altogether.

When the blowing operation is completed, cam 218 (Fig. 25) retracts the slide 214, and cam portion 219 from the cam 207 is effective for acting upon the roller 206 for swinging the arm 198 inward and with article of finished ware 220 lowered from the open blow mold to tilt therefrom to move down chute 221 (Fig. 31). Working looseness of the parts is taken up in mold closing at wedge face 199'.

Ware blowing

Cam 222 (Figs. 21, 31) acts upon roller 223 in approaching the line 181 to slide crosshead 224 outward on guide rods 225. Yieldable connection 226 is transmission from this crosshead 224 to auxiliary crosshead 227 having transverse guide way 228 (Fig. 22) for bar 229. Transverse movement of this bar 229 serves as an equalizer or compensator. From the bar 229 adjustable links 10 230 extend to angle levers 231 having fixed fulcrum 232. Adjustable yieldable links 233 from the angle levers 231 extend to the blow mold sections 178, 179.

From the cam portion 222, concentric cam 234 15 (Fig. 3) extends for holding the blow mold sections closed during the blowing operation. Cam portion 235 effects blow mold opening prior to the dropping away of the bottom 201 for discharging the finished ware.

Cam 236 (Figs. 3, 31) acts on roller 237 radially thrusting slide 238 connected by yieldable link 239 to angle lever 240 having fixed horizontal axis fulcrum 241 on the spider 194. This lever 240 carries adjustable clamp 242 for mounting blow head 243 so that in the throwing of such downward it may be nicely adjusted for seating relation in top closing of the blow mold. Concentric cam portion 244 (Fig. 3) holds this blow head in such position during the blowing interval, and cam portion 245 effects lifting of the blow head before the blow mold opening.

Pressure air for the blowing may be supplied by pipes 246 upwardly through the column 4 to ring 247 as yieldably pressed by device 248 against ring 249 (Figs. 26, 27, 28, 29, 30), 250. Handle 251 (Fig. 3) extending to the ring 249 permits a range of angular adjustment for groove 252 and ports 253 to groove 253' angularly coextensive with the ports 253. This groove 253' has 40 adjustable communication with the ports 254 in the ring 255. These ports 254 are effective through ports 256 (Fig. 24) in ring 250 for pressure air supply by line 258 to the bearing 241 and thence by duct 259 into the blow head 243 (Figs. 3, 31, 33).

In addition to such primary blowing, there may be supplemental blowing by pressure air from lines 260 extending to the ring 255, there communicating by groove 261 with the ports 256 for the timing effected by the carrier travel. In these adjustments for the two blowing operations, one may be timed as to the other for effecting a distribution of the molten glass in the ware, even for compensating when too thin at the upper portion for there making the ware more heavy, with a reverse procedure when the upper portions are too heavy and the bottom too thin. Controlled glass distribution is thus possible and the response to this control has as a factor the elapsed time from the gather up to this interval for the blowings. That is this molten condition of the glass is to an extent controlled by making longer or shorter the time blowing occurs after the gathering operation. This control is in the speed of the machine.

As the blowing operation is completed, and before mold opening, air from a line 260 at port 262 (Fig. 29) may communicate with port 263 (Fig. 24) for air blow by line 264 extending to the bearing 241 and thence by line 265 to the blow head 243 (Figs. 31, 33) to be there effective above piston 266 in depressing such against the resistance of spring 267, thereby to have pad 268 lowered upon the article of ware 220 at the

ring 80 to steady such against sticking or lateral shifting as opening of the molds occur. The article is thus left centered on the bottom 201 for definite tilting off in the ware discharged as completed from the machine.

80

Operation

The platform 1 is located in gathering proximity to the glass tank 35. The motor 7 is started by throwing in the switch 6. The meshing gears 27, 28, effect synchronous rotation of the carriers as continuously moving the series of blank and blow molds. In the instance herein shown, center lines 269, 270 (Fig. 21) for the closed blank molds and closed blow molds have a slight degree of overlapping at the center line 181 between the columns in the region of transfer. Cam portion 271 (Fig. 1) has closed the blank mold after the cooling and lubricating treatment. Dipping of the closed blank mold 45, 46, as traveling through the opening 43, effects suction gathering. Blade 112 is swung up from ahead into shearing and blank bottom closing position, for the blank forming and the plunger 73 is then retracted. The blank mold sections 45, 46, are 100 opened in the travel toward the transfer station, during which interval the burner 173 may remove shear mark and soften the blank as may be desirable. The neck ring 83 is lifted before the mold sections 53, 54, open in the vicinity of the 105 line 181, where the blow mold sections 178, 179, are closed thereabout. The blank is now carried by the second carrier for stage blowing operations in completing ware with the mold sections 178, 179, opening to leave the ware 220 on the 110 bottom 201. Tilting downward of this bottom discharges the completed ware from the machine. Inasmuch as the machine has two endless series of these blank and blow molds, the stages of blank and ware production are simultaneously 115 progressing in sequence.

The handle 251 adjusts the time of initial blow and duration thereof. This application is a continuation in part of my applications for United States Letters Patent Ser. No. 282,088, filed June 120 1, 1928, Glassware forming, and Ser. No. 99,479, filed April 3, 1926, Glass gathering and forming machines.

What is claimed and it is desired to secure by Letters Patent is:

1. A glassware forming machine comprising a rotary carrier, an auxiliary relatively shiftable member mounted on the carrier, a fulcrum for the member, a mold on the auxiliary member radially of the carrier, an air line having a valve 130 at the carrier, and a duct in a radial plane of the mold and extending from the mold toward the carrier axis to said valve, said duct providing a connection permitting movement of the auxiliary member relatively to the carrier and having 135 an arc section with its radius from said fulcrum.

2. A glassware forming machine comprising a rotary carrier, a mold movable relatively to the carrier, and a cam as to which the mold is movable by the carrier for effecting control movement of the mold, said cam including a relatively rockable terminally pivoted section having its 140 rocking axis in the general direction of the cam extent, and control means for shifting said section to adjust the horizontal plane of the mold. 145

3. A glassware forming machine comprising a rotary carrier, an open bottom mold mounted on the carrier, a closure for said mold bottom, a cam coacting for holding the closure in mold bottom closing position, a throw-out cam portion for 150

shifting the closure to mold bottom opening position, and a mounting for directing shifting of the throw-out cam portion along the other cam and angularly of the carrier.

5 4. A glassware forming machine comprising a rotary carrier, multiple element forming means mounted by the carrier, said means including a neck opening former and a second neck former thereabout, withdrawal effecting means for the

10

opening former comprising an arm extending therefrom, a cam control therefor, there being toggle linkage means coacting with said arm for locking the former in operative or withdrawn positions against movement other than cam controlled, and additional control means for the second former.

CERTIFICATE OF CORRECTION.

Patent No. 1,981,244.

November 20, 1934.

FRANK O'NEILL.

It is hereby certified that error appears in the printed specification of the above numbered patent requiring correction as follows: Page 5, line 141, claim 2, for "including" read having at all times an extent thereof effective for acting upon the carrier which said extent includes; and that the said Letters Patent should be read with this correction therein that the same may conform to the record of the case in the Patent Office.

Signed and sealed this 5th day of February, A. D. 1935.

Leslie Frazer

(Seal)

Acting Commissioner of Patents.
